UNITED STATES PATENT OFFICE.

ANDREW SCHULZE, OF WASHINGTON, DISTRICT OF COLUMBIA, ASSIGNOR
OF ONE-HALF TO EMMA S. DOUGLAS, OF ST. LOUIS, MISSOURI.

CENTRIFUGAL GOVERNOR.

SPECIFICATION forming part of Letters Patent No. 664,336, dated December 18, 1900.

Application filed March 20, 1899. Serial No. 709,846. (No model.)

To all whom it may concern:

Be it known that I, ANDREW SCHULZE, a citizen of the United States, residing in the city of Washington, District of Columbia, have 5 invented certain new and useful Improvements in Centrifugal Governors; and I do hereby declare the following to be a full, clear, and exact description of the invention, such as will enable others skilled in the art to which 10 it appertains to make and use the same.

My invention relates to certain new and useful improvements in centrifugal governors, and is particularly intended for use where high speed is desired and where it is of special utility to obtain close regulation.

In the accompanying drawings, Figure 1 represents a longitudinal sectional view of a centrifugal governor embodying my improvements. Fig. 2 represents a section thereof. 20 Fig. 3 represents a section thereof on the line 3 3 of Fig. 1. Fig. 4 represents a partial section on the line 4 4 of Fig. 1. Fig. 5 represents a section on the line 5 5 of Fig. 1; and Fig. 6 represents a top plan view, partly in 25 section.

Similar letters of reference indicate similar parts throughout the several views.

It is characteristic of my invention that the revolving elements of the governor proper are 30 inclosed within a casing in which they act as a fan, the supply of air to the casing being automatically governed by a valve having the capacity of increasing or diminishing the area of the air-inlet and even permitting the air- 35 inlet, should occasion require, to be entirely closed.

In the particular embodiment of the general idea illustrated in the drawings, w indicates the governor-stem, revolvable within 40 journals formed in the supporting-frame A and driven from the flanged belt-pulley w^3 by means of the driving-belt w^3 . Upon the stem w is fixed the disk w^9 , to which is affixed the annular plate w^{19} , leaving a recess for the reception of the disk w^{18} , said disk w^{18} having a capacity to shift somewhat in said recess. The disk w^{18} is provided with wings or beaters w^{14} , serving as fan-blades, and is also provided with extensions or lugs w^{20} , to which 45 are pivoted the weights w^{10} . The weights w^{10} are preferably of cylindrical contour and a

screw-threaded bolt w^{21} is preferably provided, so that the weight may be diminished or increased by adding to or taking away the washers w^{22} , said washers being held in place 55 by the lock-nuts w^{23} , as shown.

The weights w^{10} are preferably located opposite each other, and their tendency to separate under the action of centrifugal force may be regulated by the springs w^{24} , having hooks, 60 one of which may conveniently engage with a groove in the outer nut w^{23} and the other of which may conveniently engage with an adjusting-screw w^{25} , as shown. The weights w^{10} are connected by links w^{11} with a sleeve 65 or collar w^{12} , free to move longitudinally upon the stem w . The sleeve or collar w^{12} is adapted to bear against a collar c^9 , which constitutes a valve for the opening w^{17} of the casing w^{16} , in which the disks and the governor-weights revolve, said casing being provided with an outlet-opening w^{18} . The outward movement of the stem w^{12} is thus communicated to the valve c^9 and also to a stem c^7 or the like, leading to the throttle-valve or other 75 valve to be shifted.

It will of course be understood that the stem c^7 or the throttle or other valve to which it is connected may be provided with a spring to keep the collar c^9 in contact with the sleeve 80 w^{12} , or in some instances the suction due to the revolution of the disks and governor-weights may be relied upon for the same purpose.

Upon the belt w^3 is adapted to rest the 85 flanged idle pulley w^4 , mounted upon an arm w^5 , which arm is secured to the upper end of an arm w^6 , said arm w^6 being connected to a rocking base w^7 , having thereon an incline or cam w^8 . It will be evident that should 90 the belt w^3 break the idle pulley w^4 in its fall will revolve the rocking base w^7 , thereby introducing the cam or incline w^8 between the valve c^9 and the side of the casing w^{16} , whereupon the stem c^7 will be caused to immediately actuate the throttle-valve to close down the machine governed. A similar device to be manually operated may be provided, consisting of the rocking base w^{26} , having a link incline or cam w^{27} and a handle w^{28} , whereby 100 in any emergency the stem c^7 may be operated in like manner.

The mode of operation of the invention will be apparent. The revolution of the stem w and disk w^9 will drive the weights w^{10} , the heel portion w^{29} of said weights resting within 5 peripheral recesses w^{30} of the disk w^9 . The recesses w^{30} are inclined, and consequently as the speed of the stem w increases the weights w^{10} will rise within the recesses. Therefore the weights will be separated not 10 only by the centrifugal force exerted upon them, but also by the wedging or raising action of the inclines w^{30} , this double action sensibly increasing their range of movement. Furthermore, the inclines w^{30} will cause the 15 weights to respond very promptly to any sudden increase or diminution of speed, as will be apparent. The weights w^{10} communicate motion to the disk w^{18} , which revolves with them, and the flat end surfaces of the weights, 20 together with the wings w^{14} , serve as fan-beaters, spaced at substantially equal distances apart, and draw in a current of air through the opening w^{17} , said air being expelled through the opening w^{18} . The amount 25 of air admitted through the inlet-opening w^{17} varies with the varying positions of the valve c^9 . The arrangement is such that as the speed of rotation increases and the balls diverge more and more the valve c^9 moves 30 farther away from the inlet-opening and admits a larger and larger quantity of air, thereby progressively increasing the resistance offered by the entering air to the revolution of the governor.

35 Having thus described my invention, what I claim is—

1. A centrifugal governor, provided with an inclosing casing in which the rotating parts act as a fan and means for establishing 40 a flow of air through the casing; substantially as described.

2. A centrifugal governor, provided with an inclosing casing in which the rotating parts act as a fan, said casing being provided 45 with air inlet and outlet openings and means for varying the flow of air through the casing; substantially as described.

3. A centrifugal governor, provided with an inclosing casing in which the rotating parts act as a fan, said casing being provided 50 with air inlet and outlet openings, and a valve for increasing or diminishing the flow of air

through the inlet-opening; substantially as described.

4. A centrifugal governor, provided with 55 an inclosing casing in which the rotating parts act as a fan, said casing being provided with air inlet and outlet openings, and a valve for increasing or diminishing the flow of air through the inlet-openings, said valve being 60 actuated from the governor-stem; substantially as described.

5. A centrifugal governor, provided with swinging weights, fan-blades, an inclosing casing having inlet and outlet openings, and 65 a valve actuated from the governor-stem for increasing or diminishing the flow of air through the inlet-opening; substantially as described.

6. A centrifugal governor, provided with 70 swinging weights, a driving-disk therefor, a disk to which the weights are pivoted, said latter disk having fan-blades, an inclosing casing having inlet and outlet openings, and a valve actuated from the governor-stem for 75 increasing or diminishing the flow of air through the inlet-opening; substantially as described.

7. A centrifugal governor provided with swinging weights, a driving-disk therefor, 80 said disk having inclined recesses with which the weights engage, a disk to which the weights are pivoted, said latter disk having fan-blades, an inclosing casing having inlet and outlet openings and a valve actuated from 85 the governor-stem for increasing or diminishing the flow of air through the inlet-opening; substantially as described.

8. A centrifugal governor, provided with swinging weights, springs joining the outer 90 ends of the weights so as to oppose their outward movement, fan-blades, an inclosing casing having inlet and outlet openings, and a valve actuated from the governor-stem for increasing or diminishing the flow of air 95 through the inlet-opening; substantially as described.

In testimony whereof I affix my signature in presence of two witnesses.

ANDREW SCHULZE.
